ROLL STABILIZING DEVICE

Rupen Eksergian, Lansdowne, and Henry K. Harwick, Darby, Pa., assignors to Edward G. Budd Manufacturing Company, Philadelphia, Pa., a corporation of Pennsylvania

Application April 21, 1939, Serial No. 269,088

5 Claims. (Cl. 105—190)

The invention relates to a roll stabilizing device and more particularly to the application of such a device to railway trucks.

It is among the objects of the invention to provide a simplified construction of such a device, to incorporate it in a truck structure so as to interfere least with clearances between parts mounted on the truck and said device, to provide such a device which interferes with a minimum 10 with the usual transverse movement of the bolster and to provide such a device which can be readily installed or removed from the truck for replacement or repair.

In the preferred embodiment of the invention 15 the device is associated with a transversely swinging bolster and is interposed between the bolster and the truck frame, more particularly between the spring supported bolster and a transom connecting the side frames of the truck. More specifically it consists of a transverse torsion member pivoted to the transom and having arms rigidly secured adjacent its ends, these arms being connected to the bolster in a manner to permit free 20 transverse movement of the bolster within the usual limits.

Other and further objects and advantages and the manner in which they are attained will become clear from the following detailed description when read in connection with the drawings 25 forming a part hereof.

In the drawings:

Fig. 1 shows in top plan view a railway truck to which the improved roll stabilizing device has been applied.

Fig. 2 is a transverse vertical sectional view through the truck showing a fragmentary part of the car body mounted thereon, the section being taken substantially on the line 2—2 of Fig. 1 looking in the direction of the arrows at the ends of the section line.

Fig. 3 is a fragmentary longitudinal vertical sectional view on an enlarged scale taken approximately on the line 3—3 of Fig. 1 looking in the direction of the arrows at the ends of the section line.

Figs. 4, 5 and 6 are detail sectional views on enlarged scales showing the details of the connection of the stabilizing device to the truck parts.

The truck frame to which the device is shown 50 applied is of the type having side frames 10 and spaced transoms 11 interconnecting the side frames. The side frames are supported adjacent their ends by wheel and axle assemblies 12.

The bolster 13 is disposed between the transoms 55 11 and is supported adjacent its ends by the

springs 14. In this instance, the bolster is suspended from the frame for transverse swinging movement through swing hangers 15 hinged at the top to the transoms and supporting at the bottom the spring plank 16 upon which the bolster supporting springs 14 seat. The bolster is loosely mounted between the transoms, so as to have slight movement in the longitudinal direction of the truck between the transoms.

In this instance, the central portions of the 10 transoms and the bolster are depressed to provide a low swung support for the body indicated at 17, and engaging the truck bolster at the center bearing 18 and the side bearings 19 at the ends 15 of the bolster.

With such a truck arrangement it will be seen that when the body is under a strong tendency to tilt sideways, as when rounding a curve, there exists a tendency to overload one of the bolster springs and to decrease the loading on the other. 20 Aside from this effect on the springs such transverse tilting of the body detracts from the comfort of the passengers.

The roll stabilizer of the invention tends to minimize this lateral tilting or roll and causes 25 the bolster to compress the springs at opposite sides with about equal force.

The stabilizer consists according to the preferred form shown of a transverse bar 20 torsionally rigid and supported adjacent its ends 30 in bearing blocks 21 secured by bolts 22 to brackets 23 projecting laterally from one of the transoms 11. It projects beyond the bearing blocks and has secured to its projecting ends the rigid arms 24 keyed to the bar to prevent rotation 35 relative thereto. The key is indicated by 24' (Fig. 6). The arms may be held against longitudinal movement on the bar by split spring rings 25 located in grooves 25' on the ends of the arm.

The free ends of the arms 22 extend over the 40 bolster 13 and are pivotally connected thereto adjacent the transverse center line thereof. This pivotal connection is such as to permit freely the slight fore and aft movement of the bolster, the lateral movement due to its swinging support, 45 and also any slight tilting of the bolster with respect to the axis of the bar 20 without bending and with a minimum of friction. In other words, the connection is one permitting universal movement between the arms and bolster, and most of 50 the relative movement is through anti-friction bearings.

Since both arms are connected to the bolster in the same manner, it will suffice to describe one 55 of these connections. The arm 24 is bifurcated

at its free end having the upper and lower forks 26 and 27. The inner faces of these forks are formed with cylindrical bearing faces 28 and 29, respectively, between which is received a bearing 5 block 30 shorter than the faces 28 and 29 and having corresponding cylindrical faces engaging the faces 28 and 29, so that the block is capable of rotating around an axis extending longitudinally of the arm and of sliding in the direction 10 of said axis. This block in turn carries an anti-friction bearing 31, which in this instance consists of three annular series of balls and these engage and roll upon a bolt 32 supported on the transverse center line of the bolster by spaced 15 brackets 33 and 34, which are, in this instance integral ribs projecting from the top face of the bolster. The brackets 33 and 34 are spaced a sufficient distance from the arm 22 when the bolster is in its normal central position to permit 20 free lateral movement of the bolster in either direction to the desired extent. Cushions 35 are provided at the ends of the bolster to cushion the lateral movement of the bolster against the side frames 10.

25 The ends of the forks of the arms are secured together in properly spaced relation by spacing block 36, a U-shaped clamping member 37 and a bolt 38 passing through said block and member and the ends of the forks.

30 It will be seen from the foregoing that the device is of very rugged and practical construction, allowing freedom of movement to the bolster in its necessary movements, and at the same time constraining it against any substantial tilting 35 movement such as would result in undesirable roll and unequal loading of its supporting springs. The self-aligning bearings on the arms engaging the bolts 32 through anti-friction ball bearings insures great freedom of action and avoids undue 40 strains and wear.

By this construction the assembly is facilitated since the bar 20, bearings 21 and arms 24 may all be assembled in subassembly and secured in final assembly to the transom and bolster by simply 45 bringing the parts in position and fastening the bolts 22 and 37, the bolts 32 and bearing blocks 30 having previously been assembled with the bolster. A unit can thus be readily removed and replaced for repair or otherwise.

50 What we claim is:

1. In a railway truck, a rigid truck frame having side frames and spaced transoms rigidly interconnecting the side frames, a bolster mounted for movement transversely of said frame, disposed 55 between said transoms and spring supported adjacent its ends from said truck frame, and means for preventing transverse tilting of the bolster and unequal loading of the springs at its opposite ends, said means comprising a transverse torsion 60 rod pivoted adjacent its opposite ends on said rigid truck frame and arms rigidly secured adjacent the ends of said rod and having their free ends pivotally and slidably connected to the bolster, the 65 transverse movement of the bolster and the pivotal connection permitting limited universal movement between the arms and the bolster.

2. In a railway truck, a rigid truck frame having side frames and spaced transoms rigidly interconnecting the side frames, a bolster mounted 70 for movement transversely of said frame, disposed between said transoms and spring supported adjacent its ends from said truck frame, and means

for preventing transverse tilting of the bolster and unequal loading of the springs at its opposite ends, said means comprising a transverse torsion rod pivoted adjacent its opposite ends on said rigid truck frame and arms rigidly secured adjacent the ends of said rod and having their free ends pivotally and slidably connected to the bolster, the transverse movement of the bolster, the 10 connection being through anti-friction bearings. 15

3. In a railway truck, a rigid truck frame having side frames and spaced transoms rigidly interconnecting the side frames, a bolster mounted for movement transversely of said frame, disposed 20 between said transoms and spring supported adjacent its ends from said truck frame, and means for preventing transverse tilting of the bolster and unequal loading of the springs at its opposite ends, said means comprising a transverse torsion rod pivoted adjacent its opposite ends on said rigid 25 truck frame and arms rigidly secured adjacent the ends of said rod and having their free ends pivotally and slidably connected to the bolster, the transverse movement of the bolster, the bolster being 30 also mounted to permit slight movement in the longitudinal direction of the truck between the transoms, the connection between the arms and bolster including a second slidable connection freely permitting such movement of the bolster. 35

4. In a railway truck, a rigid truck frame having side frames and spaced transoms rigidly interconnecting the side frames, a bolster mounted for movement transversely of said frame, disposed 40 between said transoms and spring supported adjacent its ends from said truck frame, and means for preventing transverse tilting of the bolster and unequal loading of the springs at its opposite ends, said means comprising a transverse torsion rod pivoted adjacent its opposite 45 ends on said rigid truck frame and arms rigidly secured adjacent the ends of said rod and having their free ends pivotally and slidably connected to the bolster, the transverse movement of the bolster, the pivotal and sliding connection comprising a bearing on each arm rotatable and slidable on a pin 50 paralleling the torsion rod and secured between spaced integral projections from a face of the bolster. 55

5. In a railway truck, a rigid truck frame having side frames and spaced transoms rigidly interconnecting the side frames, a bolster mounted for movement transversely of said frame, disposed 60 between said transoms and spring supported adjacent its ends from said truck frame, and means for preventing transverse tilting of the bolster and unequal loading of the springs at its opposite ends, said means comprising a transverse torsion rod pivoted adjacent its opposite ends on said 65 rigid truck frame and arms rigidly secured adjacent the ends of said rod and having their free ends pivotally and slidably connected to the bolster, the transverse movement of the bolster, the connection of the torsion rod to the frame being through brackets integral with and extending laterally from a transom and the arms extend longitudinally of the truck and are secured centrally to the top of the bolster. 70
